His Attorney.

UNITED STATES PATENT OFFICE

FRANK C. DE REAMER, OF BRIDGEPORT, CONNECTICUT, ASSIGNOR TO GENERAL ELECTRIC COMPANY, A CORPORATION OF NEW YORK

WIRE CONNECTION AND METHOD OF MAKING SAME

Application filed January 29, 1931. Serial No. 512,095.

The present invention relates to the connection of wires, such as electrical conductors, to conducting members, such as contact plates, contact prongs or contact fingers. It is especially well adapted for connecting a stranded electrical conductor to a contact plate, such as the contact plate of a small switch, and accordingly the invention is specifically illustrated and described as applied to this use. It is to be understood, however, that this is only by way of example and that the invention is not limited thereto necessarily.

It has been the practice heretofore in connecting electrical conductors to conducting members to provide a hole through the member, insert an end of the conductor through the hole and then bend the conductor back on itself and twist the end one or more times about the adjacent portion of the conductor. This gives a satisfactory electrical connection but has the serious drawback, especially for some applications, that it results in a thickness at the point of connection equal to the thickness of the member plus two diameters of the wire. An instance where this drawback is especially serious is in the case of small switches such as are used in connection with radio sets, which switches may have a total width of not more than one-half inch, which means that space in the direction of the width is at a premium. Also, in making such connections, in the case of a stranded conductor, one or more strands may break or fail to be threaded through the hole with the result that a strand may project and cause a short circuit.

The object of my invention is to provide an improved wire connection and an improved method of making the same. My improved wiring connection results in a connection no wider than the thickness of the conducting member with which the connection is made, and by my improved method I am enabled to make the connections expeditiously and at low cost for labor.

For a consideration of what I believe to be novel and my invention, attention is directed to the following specification and the claims appended thereto.

In the drawing, Fig. 1 is a perspective view of a connection embodying my invention; Fig. 2 is a perspective view illustrating the conducting member and the conductor prior to being connected together; Fig. 3 is a perspective view illustrating diagrammatically the method of making the connection, and Fig. 4 is a detail view, partly in section, illustrating a fixture for use in making the connection.

Referring to the drawing, 1 indicates a conducting member or contact plate which in the present instance is one of the contact terminals of a small electric switch, 2 being the portion with which the connector of the switch contacts.

According to the embodiment of my invention illustrated in the drawing, I provide an undercut slot 3 in the member 1, the mouth 4 of the slot being of a width about equal to or slightly greater than the diameter of the wire which is to be connected to the member. 5 indicates the wire connected to the member, it being a stranded conductor as illustrated. The end of the wire 6 is pressed into the undercut slot 3 as is shown clearly in Fig. 1, it being expanded so as to fill completely the slot and be substantially flush with the surfaces of the member 1. It may be pressed into place sufficiently tight to hold it, or, if found desirable, after being pressed into place, it may be soldered or brazed to the member. The desirability of soldering or brazing depends upon the particular application to which the connection is to be put and the requirements of the particular case.

For compressing and expanding the end of the wire into the slot 3, I provide a fixture for holding the member 1 with the slot 3 in the position to receive readily the end of the wire. The end of the wire is bent at an angle as is indicated at 7, the bent over end being inserted in the slot as shown in Figs. 3 and 4. Following this, the end of the wire is compressed between two die members 8 and 9 to expand the end of the wire into the slot 3. The end of the wire is bent over so that sufficient wire is provided for filling completely the slot when the wire is compressed between the dies.

Fig. 4 shows somewhat diagrammatically a die fixture for performing the pressing operation. 10 indicates a frame upon which is mounted a die block 11 provided with a recess 12 in which is a movable spring pad comprising two blocks of metal 13 and 14 suitably fastened together and supported by spring 15. In blocks 13 and 14 is an opening 16 in which die member 9 is supported. The lower end of the die member 9 rests on the base of frame 10 in that it is stationary. Fastened on the top of the spring pad is a thin plate 17 provided with an opening of a size and shape to receive and hold a member 1 with the slot 3 in line with the die members 8 and 9. Die member 8 is carried by a rod 18 which is adapted to be moved downward by suitable means (not shown) for bringing the two die members together. In block 11 is a curved recess 19 of a size to receive the wire 5.

In use, a conducting member 1 is placed in the opening in plate 17 after which the bent down end of the wire 5 is inserted in the upper end of opening 16 as is shown in Figs. 3 and 4. The upper die member 8 is then forced downward, its end engaging over the end 7 of the wire. As the upper die member 8 is lowered, it forces the spring pad downward on the lower die member 9, and the end 7 is compressed into slot 3 between the two die members. The upper die member is then raised and the wire with the conducting member 1 thereon is removed from the fixture. This results in a construction as shown in Fig. 1. Following this, the conducting member and wire may be brazed or soldered together if found desirable.

The connection can be quickly and easily made in the fixture by a simple pressing operation, which means that the connection can be effected at low cost for labor. At the same time there results a satisfactory connection wherein the completed structure is not thicker than the plate to which the wire is connected.

What I claim as new and desire to secure by Letters Patent of the United States, is:—

1. A connection comprising a member having a transverse open ended slot extending rearwardly from an edge thereof and a wire expanded in the slot to fill the same.

2. A connection comprising a flat member having a transverse undercut open ended slot extending rearwardly from an edge thereof and a wire expanded to fill the slot.

3. A connection comprising a flat member having a transverse open ended slot extending rearwardly from an edge thereof and a stranded wire having its end expanded to fill the slot.

4. A connection comprising a member having a transverse undercut open ended slot extending rearwardly from an edge thereof, and a stranded conductor having its end ex-

panded to fill the slot, the mouth of the slot being of a width equal substantially to the diameter of the conductor.

5. The method of connecting a conductor to a flat member which comprises providing a transverse open ended slot extending rearwardly from an edge of the member and expanding an end of the conductor in the slot.

6. The method of connecting a conductor to a flat member which comprises providing a transverse open ended undercut slot extending rearwardly from an edge of the member and expanding an end of the conductor in the slot.

7. The method of connecting a conductor to a flat member which comprises providing a transverse open ended undercut slot extending rearwardly from an edge of the member, inserting a down-turned end of a conductor into the slot, and upsetting such end to fill the slot.

8. A connection comprising a member having a transverse open ended undercut slot extending rearwardly from an edge thereof and a conductor having an end bent on itself and expanded to fill the slot.

In witness whereof, I have hereunto set my hand.

FRANK C. DE REAMER.
